REPEATING MECHANISM FOR PHONOGRAPHS

Filed Jan. 26, 1920

3 Sheets-Sheet 3

UNITED STATES PATENT OFFICE.

HILMER NELSON, OF MARVINDALE, PENNSYLVANIA.

REPEATING MECHANISM FOR PHONOGRAHS.

Application filed January 26, 1920. Serial No. 354,156.

To all whom it may concern:

Be it known that I, HILMER NELSON, subject of Sweden, residing at Marvindale, in the county of McKean and State of Pennsylvania, have invented certain new and useful Improvements in Répeating Mechanism for Phonographs, of which the following is a specification.

This invention relates to phonographs, and the primary object of the invention is to provide an improved attachment for phonographs which will permit the replaying of the record when so desired by the operator.

Another object of the invention is to provide an improved means for returning the tone arm and its reproducer and stylus to its starting point on the record after the selection has been played so as to permit the repeating thereof automatically, without any attention from the operator.

A further object of the invention is to provide an improved repeating attachment for phonographs, which can be adjusted to accommodate various sized records and thereby permit the playing of any length piece and the repeating thereof in correct time.

A further object of the invention is to provide an improved repeating attachment for phonographs which is so constructed as to permit the easy placing of the stylus or needle on the record tablet for the replaying of the selection without the marring of the record or the breaking or dulling of the stylus.

A still further object of the invention is to provide an improved repeating attachment for phonographs of the above character which is durable and efficient in use, one that is simple and easy to manufacture, and one which can be placed upon the market at a reasonable cost.

Other objects of the invention will appear in the following detailed description taken in connection with the drawings, forming a part of this specification, in which drawings:

Figure 1 is a fragmentary plan view of a phonograph showing the improved attachment applied thereto, the turn table being broken away and the operating shaft or center pin shown in section.

Figure 2 is a side elevation of the tone arm of the phonograph showing the im-

proved attachment applied thereto, parts of the same being shown in section.

Figure 3 is a fragmentary detail perspective view of the lever carried by the tone arm, and the operating disc therefor, showing the resilient connection between the same.

Figure 4 is a fragmentary plan view of the phonograph attachment, showing the tone arm being returned to its starting position, and the relation of the means carried by the tone arms with the resilient means carried by the operating disc.

Figure 5 is a rear elevation of the attachment.

Figure 6 is a detail section taken on the line 6—6 of Figure 1.

Figure 7 is a detail section taken on the line 7—7 of Figure 1.

Figure 8 is a detail section taken on the line 8—8 of Figure 1.

Figure 9 is a detail section taken on the line 9—9 of Figure 1, and

Figure 10 is a detail transverse section taken on the line 10—10 of Figure 1 through the tone arm.

Referring to the drawings in detail, wherein similar reference characters designate corresponding parts throughout the several views, the letter A indicates the improved repeating attachment for the phonograph which may be of the ordinary or any preferred construction, and as shown includes the tone arm B, the reproducer C and the operating shaft or center pin D.

The tone arm B is swivelly connected to the frame of the phonograph (not shown) in the ordinary or any preferred manner and is made in a pair of sections 15 and 16, which are pivotally connected together by means of pivot pins 17. This permits the reproducer C to be lifted above the surface of the record (not shown) so as to permit the placing of the stylus in the sound groove. The outer section 16 of the tone arm B rotatably receives the hollow angle arm 18 of the reproducer and the section 16 is provided with a slot 19 for the reception of the screw 20 carried by the angle arm. The screw 20 has threaded thereon the adjusting nut 21, which is adapted to bind against the outer surface of the section 16.

The improved attachment A includes an

operating lever 22, which is pivoted intermediate its ends on a pin 23 carried by the depending bracket 24 formed on the lower surface of the tone arm section 15. The 5 outer end of the operating lever 22 is curved slightly upwardly towards the angle arm 18 of the reproducer C and carries the pivoted yoke 25, which is adapted to engage the angle arm 18, for a purpose which will 10 be hereinafter more fully described. The pivoted yoke 25 is normally held in its operative position for engaging and supporting the angle arm 18 by means of a leaf spring 26, which is secured to the lever 22 15 and engages the lower surface of the yoke which is provided with a lug 27 for engaging the forward surface of the spring to limit the swinging movement thereof. The forward end of the operating lever 22 is 20 slotted for the reception of the yoke 25, and the same is adapted to swing downwardly into engagement with the upper surface of the lever when the attachment is not to be used.

25 The tone arm section 15 directly in rear of the bracket 24 is provided with a slotted depending guide 28, which forms means for holding the lever 22 in its correct positions. The lever 22 in rear of the guide 28 is 30 provided with a depending arm 29, which is provided with oppositely extending right angularly disposed spring fingers 30, which are adapted to engage the pins 31 and 32, carried by the upper surface of the operating disc 33. The pins 31 and 32 are arranged adjacent to the periphery of the disc and the pins 32 are arranged nearer to the central axis of the disc than the pins 31 for a purpose which will be hereinafter more 35 fully described. The operating disc 33 is rotatably mounted upon the upper surface of the cabinet of the phonograph directly below the turn table (not shown), in such a manner that only a portion of the same 40 projects outwardly from the turn table. The operating disc 33 is rotated from the operating shaft or center pin D which has a pulley 34 mounted thereon. The pulley 34 has trained around the same a belt 35, 45 which drives the relatively small disc 36. The relatively small disc 36 and the disc 33 are connected together by a suitable belt 37. The addition of the wheel 36 forms means for reducing the speed of rotation of 50 the operating disc 33 in relation to the turn table. The outer edges of the discs 33 and 36 are provided with peripheral grooves 38 for the reception of the drive belts 35 and 37. The resilient fingers 30 are adapted to be 55 normally held above the surface of the pins 31 and 32, but when the inner end of the lever is lowered by means hereinafter more fully described, the pins engage the spring fingers and swing the tone arm over the 60 turntable. The inner end of the operating lever 22 is curved outwardly as at 39, so as to conform to the configuration of the tone arm B and the extreme inner end is provided with a weight 40 which tends to counterbalance the weight of the tone arm 70 section 16 and the reproducer C.

Immediately in rear of the operating disc 33 and in front of the point of connection of the tone arm B with the cabinet, an arcuate base plate 41 is arranged on the upper surface of the phonograph by suitable fastening elements. The upper surface of the base plate 41 has secured thereto the arcuate guide tracks 42 in which is slidably mounted the arcuate vertical adjusting plate 43. The lower end of the arcuate vertical adjusting plate 43 is provided with a right angularly extending base 44, which is mounted in the guide tracks. The upper edge of the plate 43 intermediate its ends is provided with inwardly extending spaced right angularly extending lugs 45, and 46. The lug 46 is formed relatively wider and broader than the lug 45 and the space intermediate the lugs is just sufficient to receive the inwardly extending foot 47, for a purpose which will be hereinafter more fully described. The arcuate plate 43 is held in its adjusted position by a spring clamp 48 which includes a pair of arms 49 having overlapping inwardly extending ears 50 which are pivotally mounted upon the reduced portion 51 of the upwardly extending stud 52, which is provided with an attaching plate 53 which is secured in position on the upper end of the cabinet of the phonograph by suitable screws 54. The inner terminals of the arms 49 carry suitable friction pads 55 which are adapted to engage the opposite faces of the plate 43. The inner terminals of the arms 49 are normally held in engagement with the opposite faces of the plate by a coil spring 56, which is coiled around the reduced portion 51 of the stud 52, and has the opposite ends thereof 100 engaging the inner faces of the arms.

The lever 22 in rear of the depending arm 29 is provided with a pair of spaced upwardly extending cut-out portions or notches 57 and 58 and the notch 57 has the rear wall thereof provided with the inwardly extending foot 47, which is adapted to ride over the top surface of the lug 46 when the tone arm is moving over the record and is adapted to engage under the lug 46 when the tone arm is being moved back to its original starting place. The notch 58 is provided with an inwardly extending foot 59, which is formed on the rear wall thereof and the foot is adapted to ride over the upper surface of the rearwardly extending lug 60, formed on the adjusting plate 61 when the tone arm is moved over the record in 105 110 115 120 125

playing position and adapted to engage the under surface of the lug when the tone arm is being moved back to its original playing position. The adjusting plate 61 includes 5 an angular extending base 62, which is slidably mounted on the upper surface of a relatively small plate 63, which is riveted or otherwise secured as at 64 to the upper surface of the base plate 41 in rear of the arcuate adjusting plate 43. The relatively small plate 63 covers a slot 65 formed in the plates 41, and the plate 63 is provided with a relatively small longitudinally extending slot 66, through which the rivet 67 slidably extends. This arrangement forms means for 10 slidably mounting the plate 61 on the upper surface of the base plate 41 for a purpose which will be hereinafter more fully described. The plate 61 is adjusted longitudinally of the base plate 41 by means of a screw 68, which is threaded into a nut 69 carried by the plate 61. The screw 68 is rotatably mounted upon an upstanding lug 70 formed on the upper surface of the base plate and 15 is provided with an operating head or thumb piece 71. Movement of the screw in relation to the lug 70 is prevented by the collars 72 formed on or carried by the screw which engage the outer faces of the lug. It can be 20 seen by turning the screw, the plate 61 will be moved toward or away from the lug 46, for a purpose which will be hereinafter more fully described.

Mounted on the base plate 41 intermediate 25 the plate 43 and the plate 60 is an arcuate leaf spring 73, which has one terminal thereof provided with an attaching foot 74, which is riveted or otherwise secured as at 75 to the upper surface of the base plate 41. The leaf spring 73 extends from the end 30 of the base plate 41 adjacent to the clamp 48 toward the lug 70 and has its free end provided with the upwardly and forwardly extending portion 76, which lies in a plane 35 above the main body portion 77. The lower face of the spring 73 is adapted to be engaged by the inwardly extending foot 78 of the arm 79, formed on the lower surface 40 of the lever 22 intermediate the notches 57 and 58.

In the operation of the improved device 45 the tone arm B is moved toward the center of the record and the stylus carried by the reproducer D is placed in the last sound groove after which the clamp 48 is operated so as to release the plate 43, which is moved, so as to position the space intermediate the lugs 45 and 46 in direct alignment with the foot 47. Thus when a record is through 50 playing, the foot 47 will be directly over the opening between the lugs 45 and 46. After this initial adjustment the reproducer is then moved over to the first sound groove and the machine is started in the ordinary manner. 55 When the tone arm is being moved over the

record the foot 47 rides over the upper surface of the lug 46 and the foot 59 rides over the upper surface of the lug 60, while the foot 78 of the arm 79 engages the under surface of the spring 73, and when the foot 78 60 engages the curved portion of the spring and rides under the main portion 77 of the spring and the end of the record is reached, the pressure of the spring will force the foot 47 into the declivity between the lugs 75 45 and 46, thus rocking the lever 22 on its pivot 23, which will raise the section 16 of the tone arm B on its pivot 17 and the stylus of the reproducer C out of the last sound groove and above the surface of the record 80 and dispose the spring fingers 30 of the arm 29 in the path of the pins 31 and 32. When the pins 31 and 32 engage the spring fingers 30, the same will move the tone arm back over the top surface of the record and drop 85 the stylus in the outer sound groove. The plate 43 is adjustable so that the repeating attachment can be used on records of a different length as all selections do not end at same point on the record tablet. 90

The plate 61 is also formed adjustable, so that in case records are provided with a larger outer margin than other records the same can be accounted for, although it has been found that records of one make all 95 start from practically the same point. Thus it can be seen that when the foot 47 rides from under the lug 46, the foot 59 will engage under the lug 60 and when the foot 59 rides from under the lug 60, the reproducer will be dropped. 100

To reduce the force of the drop of the stylus on the record, a leaf spring 80 is secured at one end as at 81 adjacent each of the pins 31 and 32 and the pin 31 is adapted 105 to catch the outer spring finger 30 and move the same under the spring 80 which gently lowers the needle on the record.

The plate 61 and lug 60 is only adapted for use in playing ten inch records and when 110 the twelve inch records are to be played, the attachment 82 is moved into position.

The attachment 82 includes the angular arm 83 which is mounted upon a post 84, rotatably mounted in a sleeve 85, which is provided with a base 86 which is riveted or otherwise secured as at 87 to the base plate 41 adjacent to the outer end thereof. The sleeve 85 is provided with a slot 88 in which is slidably mounted the lug 89 which limits the swinging movement of the post. The inner end of the angular arm 83 is provided with a notch 90 at its inner face, and this notch forms means for permitting the foot 59 to ride out of engagement with the arm 83 when the end of the twelve inch record 115 is reached. It can be seen that when a twelve inch record is placed, the post is turned so as to bring the inner end of the angular arm 83 in alignment with the lug 120 125 130

60 and the foot 59 will ride out of engagement with the lug 60 into engagement with the lower surface of the arm 83 until the notch 90 is reached. The upper end of the 5 post is provided with a thumb piece 91, by means of which the same may be readily turned. The post 84 has also mounted thereon an outwardly extending arm 92, provided with a flat head 93 which may be swung into 10 the path of the tone arm if so desired for limiting the movement thereof to prevent the same from being swung off of the record. An expansion spring 94 is coiled around the post 84 intermediate the angle arm 83 and the 15 upper surface of the sleeve 85 and this spring is carried by the post and exerts a pressure on the upper surface of the sleeve so as to form a frictional lock for the post and prevent accidental turning movement in 20 the sleeve or bearing 85.

From the foregoing description, it can be seen that an improved attachment is provided for phonographs which will permit the repeating of the selection without any attention of the operator after the repeating attachment has been once set.

The pins 31 and 32 are spaced a sufficient distance apart so as to permit the riding of the spring fingers 30 therebetween. The pins 30 31 are adapted to move the tone arm when ten inch records are being played and the spring fingers are adapted to ride above the pin 32 when the end of the record is reached. When the angle arm 83 is swung in position 35 so as to hold the spring fingers 30 in their lowered position for playing twelve inch records, the pin 32 is adapted to engage the spring fingers 30 after the pins 31 and swing the tone arm to the first sound groove of the 40 record.

Changes in details may be made without departing from the spirit or scope of my invention; but,

I claim:

- 45 1. The combination in a phonograph having a swinging tone arm and a pivoted sound box on said arm, a lever pivoted on the tone arm and connected at one end to the sound box, power transmitting means adapted to be operated by the turntable shaft of the phonograph for engaging the lever and swinging the tone arm to its original position, resilient means arranged to operate on the lever and adapted to raise the sound box 50 at a predetermined point, a movable member operable by the turntable shaft, and resilient retaining means on said movable member adapted to engage, swing and lower the lever at a predetermined point.
- 55 60 2. The combination in a phonograph having a swinging tone arm and a sound box on the outer end thereof, a lever pivotally mounted on the tone arm intermediate its ends and connected at one end with the sound 65 box, a movable member connected to the

phonograph for operation by the turntable shaft of the phonograph, means on the lever for engagement with the movable member to return the tone arm to its original position, a resilient device engaging the lever to elevate the sound box and swing the same, retaining means engaging the lever to prevent swinging thereof until a predetermined point is reached, and adjusting means for the retaining means, whereby said lever may be 70 released at a predetermined point for operation by said resilient means to move the lever into the path of the movable member.

3. The combination in a phonograph including a tone arm having a pivoted end, 80 a sound box carried by the pivoted end, and a turntable shaft, rotatable means below the tone arm operable from said shaft, means carried by the tone arm arranged normally in the path of the rotatable means, means holding said tone arm carried means out of the path of said rotatable means, and means for swinging the tone arm carried means into engagement with the rotatable means at 85 a predetermined point.

4. The combination with a phonograph including a swinging tone arm having a pivoted end and a sound box carried by the pivoted end, of a repeating attachment for the phonograph including a rotatable member, a lever pivotally carried by the tone arm, the lever being arranged to engage the pivoted end of the tone arm, the opposite end of the lever being arranged to engage the rotatable means, spring means for moving the lever into engagement with the rotatable means and for lifting the sound box, and means normally holding the lever out of operative position with the rotatable means until a predetermined point has been 90 reached.

5. The combination with a phonograph including a swinging tone arm, a sound box and a turn table and pin, of a repeating attachment therefor including a flat rotatable member operatively connected with the turn table pin and disposed below and projecting outwardly of the turn table, a lever pivotally mounted intermediate its ends upon the tone arm, means formed on the lever and arranged to be projected into the path of the rotatable means, means for moving said means into the path of the rotatable means, and means for normally holding the lever carried means out of the path of the rotatable means until a predetermined point has been reached.

6. The combination with a phonograph including a swinging tone arm having a pivoted end, a sound box carried by the pivoted end and a turn table and pin, of a repeating attachment for the phonograph including a rotatable member disposed below and projecting outwardly of the turn table, a lever pivotally mounted intermediate 125

ate its ends upon the tone arm, the forward end of the lever being adapted to engage pivoted end of the tone arm, a depending foot carried by the rear end of the lever and 5 adapted to be projected into the path of the rotatable means when the lever is swung upon its pivot, means for swinging the lever upon its pivot, and means for holding the lever against swinging movement until a 10 predetermined point has been reached.

7. The combination with a phonograph including a swinging tone arm having a pivoted end and a sound box carried by the pivoted end, of a repeating attachment 15 for the phonograph including a rotatable member, a lever pivoted intermediate its ends upon the tone arm, the forward end of the lever being adapted to engage the pivoted end of the tone arm, a depending 20 foot carried by the rear portion of the lever and adapted to be projected into the path of the rotatable means when the lever is swung upon its pivot for raising the sound box, spring means adapted to swing the 25 lever upon its pivot for raising the sound box and for moving the foot into the path of the rotatable means, and adjustable means for holding the lever against swinging movement until a predetermined point 30 has been reached.

8. The combination with a phonograph including a swinging tone arm having a pivoted end, and a sound box carried by the pivoted end, of a repeating attachment for 35 the phonograph including a rotatable member, a lever pivotally mounted intermediate its ends upon the tone arm, a yoke carried by the forward end of the lever for engaging the pivoted end of the tone arm for lifting 40 the sound box upon swinging movement of the lever, a depending foot carried by the rear end of the lever arranged to be projected into the path of the rotatable means when the lever is swung upon its pivot, 45 means for swinging the lever upon its pivot, and adjustable means for preventing swinging movement of the lever until a predetermined point has been reached.

9. The combination with a phonograph 50 including a swinging tone arm having a pivoted terminal, and a sound box carried by the pivoted terminal, of a repeating attachment for the phonograph including a rotatable member, a lever pivotally mounted 55 intermediate its ends upon the tone arm, a pivoted yoke carried by the forward end of the lever adapted to support the pivoted end of the tone arm when in its raised position or lie below the pivoted end of the tone 60 arm when moved to its lowered position, a depending foot carried by the rear end of the lever and adapted to be moved into the path of the rotatable means upon swinging movement of the lever, spring means for 65 swinging the lever on its pivot, and means

for preventing the swinging movement of the lever until a predetermined point has been reached.

10. The combination in a phonograph including a swinging tone arm having a pivoted end and a sound box carried by the pivoted end, of a repeating attachment including a lever pivotally mounted intermediate the ends of said tone arm upon the lower surface thereof, means carried 70 by the forward end of the lever for engaging the pivoted end of the tone arm, means on the lever adjacent to the pivot and adapted to be projected into the path of the rotatable means for swinging the tone 75 arm to its original position, resilient means for swinging the lever on its pivot for raising the sound box, rotatable means for swinging the lever carried means, means for preventing the swinging movement of the 80 lever until a predetermined point has been reached, means for releasing the lever after the tone arm has moved to its original position, and spring means for regulating the 85 swinging of the lever after said original 90 position is reached.

11. The combination with a phonograph including a swinging tone arm having a pivoted terminal, and a sound box carried by the pivoted terminal, of a repeating attachment for the phonograph including rotatable means arranged below the tone arm, upstanding pins arranged adjacent to the periphery of the rotatable means, means for rotating said rotatable means, a lever pivotally mounted intermediate its ends upon the tone arm, a yoke carried by the forward end of the lever and arranged to engage the pivoted end of the tone arm, a depending foot carried by the opposite end of the lever and arranged to be projected into the path of the pins when the lever is swung upon its pivot, adjustable means arranged to engage the lever to prevent swinging movement thereof until a predetermined point has been reached, spring means for swinging the lever, and adjustable means for permitting the return of the lever to its normal position when the tone arm has 100 been swung back to its starting position. 110

12. The combination with a phonograph including a swinging tone arm having a pivoted end, a sound box carried by the pivoted end of the tone arm, a turn table, a center pin turning the turn table, a rotatable disc arranged below the turn table and having a portion thereof projecting outwardly of the turn table, means for rotating the disc from the center pin, pins carried by the disc and arranged adjacent to the periphery thereof, a lever pivotally mounted intermediate its ends upon the tone arm, a yoke carried by the forward end of the lever and arranged to engage the pivoted end of the tone arm, a depending 120 125 130

arm carried by the lever, spring fingers formed on the arm arranged to engage the pin, a foot carried by the lever, an adjustable plate, a lug formed on the upper surface of the plate and arranged to engage the foot formed on the lever for holding the lever in a raised position, spring means arranged to swing the lever, and means carried by the disc for cushioning the lowering movement of the sound box.

13. The combination with a phonograph including a swinging tone arm having a pivoted end, a sound box carried by the pivoted end, a turn table, and a center pin supporting the turn table, of a repeating attachment for the phonograph including a rotatable disc arranged below the turn table and having a portion thereof projecting outwardly of the turn table, pins arranged on the upper surface of the disc adjacent to the periphery thereof, resilient means arranged adjacent to the pins, a lever pivotally mounted intermediate its ends upon the tone arm, a yoke carried by the forward end of the lever and arranged to engage the pivoted end of the tone arm, a depending arm carried by the lever, resilient fingers formed on the arm and arranged to be moved into the path of the pin when the lever is swung on its pivot for returning the tone arm to its normal position, an adjustable plate arranged in rear of the disc, a lug formed on the upper surface of the plate, a foot carried by the lever arranged to engage the lug to hold the lever in its raised position, a second foot carried by the lever, resilient means arranged to engage said foot to swing the lever on its pivot for raising the pivoted end of the tone arm and for moving the fingers into the path of the pins, a second adjustable plate arranged on one side of the first named plate, an inturned lug formed on the second plate, and a third foot arranged to engage the lug.

14. The combination with a phonograph including a swinging tone arm having a pivoted end, a sound box carried by the pivoted end, a turn table, and a center pin supporting the turn table, of a repeating attachment for the phonograph including a rotatable disc arranged below the turn table and having a portion thereof projecting outwardly of the turn table, means for rotating the disc from the center pin, means for reducing the speed of the disc in relation to the turn table, a lever pivotally mounted intermediate its ends upon the tone arm, a yoke carried by the forward end of the lever for engaging the pivoted end of the tone arm, a weighted plate carried by the opposite end of the lever, a depending arm formed on the lever intermediate its ends and in rear of the pivot pin, resilient fingers formed on the arm,

upstanding pins carried by the upper surface of the disc and arranged adjacent to the periphery thereof, the fingers being adapted to be projected into the path of the pins upon swinging movement of the lever for moving the tone arm to its original starting position, a base plate arranged in rear of the turn table, a guide track carried by the base plate, a plate slidably mounted in the track, means for holding the plate in adjusted position on the track, inturned lugs formed on the upper surface of the plate, a foot formed on the lever arranged to engage the lug for holding the lever in its raised position, an arcuate spring having one terminal secured to the plate, the spring having its outer end arranged in a plane above its inner end, a depending foot carried by the lever arranged to engage under the spring for swinging the lever on its pivot, a plate adjustably carried by the base plate, means for adjusting the plate, an inturned lug formed on the plate, a third foot carried by the lever and arranged to engage the last mentioned lug, and resilient leaf springs carried by the periphery of the disc for engaging the fingers carried by the arm for cushioning the lowering movement of the sound box, when the tone arm has been swung to its original position.

15. The combination with a phonograph including a tone arm having a pivoted end, a sound box carried by the pivoted end, a turn table, and a center pin supporting the turn table, of a repeating attachment for the phonograph including a rotatable disc arranged below the turn table and having a portion thereof projecting beyond the turn table, means for rotating the disc from the center pin, a lever pivotally mounted intermediate its ends upon the tone arm, a yoke carried by the forward end of the lever for engaging the pivoted end of the tone arm, a depending arm carried by the lever, spring fingers carried by the lower end of the arm, upstanding pins carried by the disc adjacent to its periphery, means for swinging the lever on its pivot for raising the pivoted end of the tone arm, adjustable means for holding the lever against swinging movement until the tone arm has reached a predetermined position, an adjustable plate arranged adjacent to the means, an inturned lug formed on the adjustable plate, a foot carried by the lever and arranged to engage the inturned lug, and a pivoted arm arranged adjacent to the plate and adapted to be brought into alignment with the lug, said arm having a notch formed therein arranged to receive the foot.

16. The combination with a phonograph including a swinging tone arm, of a repeating attachment therefor including a pivoted

lever carried by the tone arm, means for swinging the lever on its pivot, means for normally holding the lever against swinging movement until the tone arm has 5 reached a predetermined position, and means for releasing the lever when the tone arm has been returned to its original position, a stop for the tone arm, and means carried by the stop adapted to be brought into and out of alignment with the releasing means for the tone arm. 10

In testimony whereof I affix my signature.

HILMER NELSON.
